INTERLOCKING DEVICE FOR STORAGE CABINETS

Jacob Mandel, New York, N. Y., assignor to
 Promto File Corporation, New York, N. Y., a
 corporation of New York

Application October 16, 1942, Serial No. 462,269

8 Claims. (Cl. 312—111)

The present invention relates to individual files adapted to be stacked one above the other and to be arranged in adjacent vertical columns, and more particularly to collapsible storage files of the drawer and casings type made predominantly of paper board stock and reinforced at various points, and particularly at the open front end of the casing with metallic members.

It is the general object of the invention to provide improved interlocking means for interconnecting adjacent files, and especially horizontally adjacent files, to each other in a simple and expeditious manner.

It is further object of the invention to provide locking means for interconnecting horizontally adjacent files so as to prevent relative displacement in either the horizontal or vertical direction, such locking means being separate and independent of connecting devices provided for connecting vertically superposed files to prevent horizontal displacement therebetween.

It is also an object of the invention to provide interlocking means for horizontally adjacent files which does not increase, or does not substantially increase the spacing otherwise necessary between the horizontal adjacent files.

It is a still further object of the invention to provide an interlocking structure for horizontally adjacent files which interengages directly with the reinforcing members at the front, open ends of the casings, whereby interconnecting mechanism for the vertically superposed files can be formed as completely flat members, and without the necessity for the provision of projecting elements for engaging and interlocking horizontally adjacent casings, as shown in the patent to Sol Scheinman, No. 2,277,155, issued March 24, 1942, over which the present invention is an improvement.

Other objects and advantages of the invention will appear more fully from the following detailed description of the invention, and the features of novelty will be set forth in the subjoined claims.

A satisfactory embodiment of the invention is illustrated by way of example in the accompanying drawing, wherein Fig. 1 is a front end view in elevation, partly broken away, and showing a battery of four casings composed of two horizontally adjacent columns, each having two superposed casings, and showing my improved mechanism for interconnecting superposed casings and for interlocking horizontally adjacent casings.

Fig. 2 is a partial side view showing two superposed casings held against relative horizontal movement by an interconnecting member, and

showing also the locking key in position on one of the casings.

Fig. 3 is an enlarged view of the interconnecting member and is taken along the line III—III of Fig. 4.

Fig. 4 is an enlarged view, partly in section, showing one of the interlocking members.

Fig. 5 is a fragmentary view showing the initial position of the locking key for engagement with the side reinforcing member of the casing.

Fig. 6 represents a vertical section taken along the line VI—VI of Fig. 5.

Fig. 7 shows the locking key in rotated, locking position.

Fig. 8 is a horizontal section along the line VIII—VIII of Fig. 7.

The invention is illustrated on the drawing as applied to collapsible, reinforced paper storage files of the type shown in the patent to Scheinman and Mandel, No. 2,110,556, issued March 8, 1938. The main body 10 of the casing of the file is made of corrugated or other paper stock, and is reinforced at its open front end by metallic reinforcing members which may be separate from each other, as shown in the last mentioned patent, or united to form a unitary, rigid frame 11 which is slipped on the open end of the erected casing and secured thereto in any suitable manner. The body of the casing can, of course, be made of other material than paper, and as the structure of the casing itself and of its specific reinforcement forms no part of the present invention, it need not be described in further detail.

The side reinforcing members 12 of the casing are provided at their upper ends with a pair of socket members or straps 13, and at their lower ends with a similar and symmetrically positioned pair of sockets or straps 14 struck from the body of the side reinforcing member. These sockets are adapted to receive snugly the upper and lower shanks or extensions 15 and 16, respectively, of an interconnecting member 17, as best seen in Fig. 3, the shanks 15 and 16 passing through and beyond the lower and upper socket of the lower and upper pairs of sockets. The intermediate portion 18 of the interconnecting member is of square or oblong form, and is wider than the shanks 15 and 16 to provide shoulders 19. The height of the central portion 18 is so determined that in the assembled condition, shown in Fig. 3, the shoulders engage the adjacent edges of the walls of the inner of each pair of sockets or straps. In this way, the interconnecting members aid in transmitting the vertical load from

a superposed casing to that immediately beneath it.

It will be noted that the interconnecting members 17 are stamped from flat stock, there being no projections on these members which will have the effect of increasing the clearance space between two horizontally adjacent columns of files, such spacing being determined entirely by the contacting socket walls of horizontally adjacent files, as can be seen from Figs. 1 and 4.

In order to lock adjacent vertical columns of files against displacement in any direction, and especially in the horizontal direction (as when a heavily loaded drawer is withdrawn from its casing), I provide a locking key which engages directly with the side reinforcing members of the casing and fits snugly into the space between horizontally adjacent files and provided by the contacting socket members 13 and 14. To this end, I provide a locking key 20 which, like the interconnecting member 17, can be made of metal or of any sufficiently rigid material, like vulcanized paper, resin-impregnated paper, or the like, such locking key fitting within the narrow space normally present between contacting, horizontally adjacent files. The key engages portions of the side wall reinforcing members removed from the socket members 13 and 14, there being provided interengaging lugs and recesses of such nature that upon rotation of the key, the horizontally adjacent files are securely locked together.

In the form of the invention illustrated, the key 20 is roughly in the form of an L-shaped structure, and it is composed of two spaced plates joined along the edge 21, the key being preferably formed from a roughly Y-shaped blank which is bent along the central line 21. Upon each side of the key, there are struck a pair of oppositely facing lugs 22, the inner surfaces of the lugs being spaced from the adjacent surface of the key by a distance slightly larger than the thickness of the reinforcing member on the side walls of the casing. These reinforcing members are provided, preferably at their central portions, with elongated slots 23 of such shape as to accommodate snugly a pair of lugs. As will be readily understood, upon passing a pair of lugs into the aperture 23 of a reinforcing member on one casing and then moving the horizontally adjoining casing into position to bring the apertures in the reinforcing member of such casing into engagement with the opposite pair of lugs, each pair of lugs being then positioned beyond and rearwardly of the adjoining reinforcing member, and upon rotation of the key from the position shown in Fig. 5, to that shown in Fig. 6, the lugs will be brought into a position in which they securely lock the adjacent reinforcing members on the horizontally adjoining files in the manner of a bayonet or turnbutton type of joint. As can be seen from Figs. 6 and 8, the lugs are located entirely inside of the reinforcing members, and the outer surfaces of the main body of the key are in close contact with the outer surfaces of the reinforcing members. As the total thickness of the body of the key is preferably no more than the clearance provided by the engagement of the socket members 13 and 14 on horizontally adjacent casings, no increase in the clearance between such casings is made necessary by the provision of the locking key 20.

The general outline of the pair of lugs 22 will be similar to that of the elongated apertures 23; and the distance between the outer edges of the lugs will be substantially greater than the width

of the apertures. This will insure that the lugs will penetrate a sufficient distance behind the walls of the apertures 23 to provide a firm interlock.

5 The key is preferably so dimensioned, and the apertures 23 are so located, that in the locking position, the key will be located inwardly of the front edges of the casings; preferably, the forward longitudinal edge 21 of the key is more or less flush with the front edges of the casings, so that the key can be easily engaged at its bottom edge with the finger and rotated outwardly, should it be desired to release the casings. In this way the key is made inconspicuous and at the same time readily accessible.

10 20 The key 20 may be provided with a through aperture 24, through which a wire may be passed for securing the key to the reinforcing metallic frame or to any other part of the casing to prevent loss of the key in transit.

15 25 While I have shown the lugs as located on the locking key and the apertures or slots on the reinforcing members, it is obvious that these structures can be reversed, that is, the lugs can be positioned on the reinforcing members, and the elongated slots on the key. Other variations from the specific structure illustrated can be resorted to within the scope of the appended claims without departing essentially from the spirit of the invention.

30 I claim:

1. The combination of a pair of horizontally adjacent files each composed of a drawer and casing and having vertical metallic members at the side wall front edges thereof, and socket elements struck from and projecting from the body of said metallic members at the top and bottom thereof to receive a connecting member for locking the casing to a superposed casing, 35 said casings being adapted to be assembled in a battery of files wherein horizontally adjacent casings are in contact at the projecting socket elements, and a locking member having a body provided with means engaging the metallic members of horizontally adjacent casings to hold the same against horizontal displacement, the body of said locking member fitting wholly within the limited clearance space between the facing vertical metallic members on horizontally adjacent casings and formed when the socket elements are in lateral engagement.

40 45 50 55 2. The combination as set forth in claim 1, wherein the locking member is in the form of a substantially L-shaped key and wherein the longitudinal edge of the key is substantially flush with the front edges of the casings when the key is in locking position.

60 65 70 75 3. The combination with a pair of horizontally adjacent casings having elongated apertures in the facing side walls thereof, of a locking key comprising a handle portion and a body portion having locking lugs on each side of the body portion thereof, said lugs having portions spaced a sufficient distance from the body of the key to enable the walls of the elongated apertures in the said casings to be received between said lugs and the body of the key, the lugs on the opposite sides of the key being insertable simultaneously within the elongated apertures of adjacent casings, the distance between the outer ends of the lugs being greater than the width of the apertures, whereby upon rotation of the key after entry of the lugs into the said apertures, said lugs become interlocked with the walls of the apertures, the angle between the

body of the key and the handle thereof being such that upon said rotation, the key is disposed wholly between the adjacent casings.

4. The combination with a pair of horizontally adjacent casings, having elongated apertures in the facing side walls thereof, of a locking key having oppositely facing lugs on each side thereof, said lugs being spaced a sufficient distance from the body of the key to enable the walls of the elongated apertures in the side walls of said casings to be received between said lugs and the body of the key, the distance between the outer ends of the lugs being greater than the width of said apertures but not greater than the length thereof, whereby upon rotation of the key through about 90°, after insertion in a pair of aligned apertures, said lugs become interlocked with the walls of said apertures, the key being of substantially L-shape and being composed of a piece of sheet metal bent over on itself along a central line.

5. A locking key for horizontally adjacent casings, said key being formed into two spaced plates by bending a piece of sheet metal on itself, and having oppositely facing lugs on each of said plates, said lugs having overhanging portions spaced from the said plates to enable a metal plate to be received and gripped between said lugs and the respective plates, the distance between the outer ends of the lugs on either plate being greater than the width of the lugs.

6. The combination with a pair of horizontally adjacent casings having elongated apertures at

the facing side wall marginal portions thereof, of a locking key having oppositely facing lugs on each side thereof, said lugs being spaced a sufficient distance from the body of the key to enable the walls of the elongated apertures in the side walls of said casings to be received between said lugs and the body of the key, the distance between the outer ends of the lugs being greater than the width of said apertures, whereby upon rotation of the key through about 90°, after insertion in a pair of aligned apertures, said lugs become interlocked with the walls of said apertures, said key having a handle portion adapted to project beyond the front edges of the side walls of the casings when the lugs are interengaged with said apertures and movable to a position inwardly of said front edges on said rotation.

7. The combination as set forth in claim 1, including connecting members constituted of flat stock and fitted into the adjacent socket elements of superposed files.

8. The combination as set forth in claim 1, wherein the vertical metallic members are provided with elongated apertures intermediately of the top and bottom socket members, the said means on the locking member comprising elements having overhanging portions which fit into aligned apertures on horizontally juxtaposed casings and on rotation of the key grip behind the walls of the apertures to lock such casings together.

JACOB MANDEL.
